UNITED STATES PATENT OFFICE.

ISAAC N. BAKER, OF BAY CITY, MICHIGAN.

SELF-CLOSING FAUCET.

SPECIFICATION forming part of Letters Patent No. 791,238, dated May 30, 1905.

Application filed June 5, 1903. Serial No. 160,229.

To all whom it may concern:

Be it known that I, ISAAC N. BAKER, a citizen of the United States, residing at Bay City, in the county of Bay and State of Michigan, have invented certain new and useful Improvements in Self-Closing Faucets; and I do hereby declare the following to be a full, clear, and exact description of the invention, such as will enable others skilled in the art to which it appertains to make and use the same.

This invention is a self-closing faucet; and the objects of the invention are to provide simple means whereby the faucet-handle when released will be automatically returned to its closed position, shutting off the flow.

My invention is illustrated in the accompanying drawings, in which—

Figure 1 is a perspective view of a faucet making use of my improvement. Fig. 2 is a front view, and Fig. 3 is a top view.

As is clearly shown in the drawings, the device consists in a projection 1, fixed to the faucet-handle 2, engaging the face of a flat spring 3, which is secured to the body of the faucet by a bracket 4.

When the handle is turned to open the faucet, the projecting end 1 bears against and slides over the face of the upright spring 3, pressing it back, as shown by dotted lines in Fig. 1, and when the faucet-handle is released the spring 3 in returning to its normal upright position presses against the projection 1 and closes the faucet.

The spring 3 may be made of steel or other suitable material and is preferably held in place by being fitted into a slot 4^a of the bracket 4 and further secured by bolts 4^b. The spring 3 can thus be easily and quickly replaced if bent or broken.

By the means above described I have produced a simple and inexpensive self-closing device for faucets and one that is not liable to get out of order.

What I claim as my invention, and desire to secure by Letters Patent, is as follows:

In a self-closing faucet the combination with the faucet-body of a laterally-extending vertically-slotted bracket formed integral with said body; a vertical flat spring removably secured in said slotted bracket and a projection carried by the faucet-spindle opposite said handle and integral therewith, and adapted to bear against one side of said vertical flat spring when the faucet is opened in one direction only and to be restored to its original position by said vertical flat spring when the faucet-handle is released, substantially as described.

In testimony whereof I affix my signature in presence of two witnesses.

ISAAC N. BAKER.
